UNITED STATES PATENT OFFICE.

CLAIBOURNE FREMONT JACKSON, OF LAS MINAS, CUBA.

MAIL-CATCHER.

1,156,844.

Specification of Letters Patent. Patented Oct. 12, 1915.

Application filed October 3, 1914. Serial No. 864,911.

To all whom it may concern:

Be it known that I, CLAIBOURNE FREMONT JACKSON, a citizen of the United States, residing at Las Minas, in the Republic of Cuba, have invented certain new and useful Improvements in Mail-Catchers, of which the following is a specification.

This invention relates to a mail catcher and the principal object of the invention is to provide improved means for delivering a mail bag from a holding apparatus to a chute so that the mail bag can be delivered to a moving train or from a moving train to a station device.

Another object of the invention is to provide an improved type of spring gun for delivering the mail bag to the train device.

Another object of the invention is to provide an improved type of trough which is mounted alongside the track to receive the mail bag delivered from the train.

Another object of the invention is to provide improved means for setting the spring plungers of the station gun and to also provide improved means for releasing the spring plunger.

Another object of the invention is to provide improved means for suspending a sack to be delivered from the train and to also provide improved means for releasing the sack and permitting it to drop into the station trough.

This invention is illustrated in the accompanying drawings, wherein—

Figure 1 is a view in elevation showing the station gun in a set position with a mail car in a position to actuate the means for releasing the spring plunger; Fig. 2 is an end elevation of the structure shown in Fig. 1; Fig. 3 is a transverse sectional view taken along the line 3—3 of Fig. 1; Fig. 4 is a plan view of the means for suspending a sack to be delivered from the train; Fig. 5 is a perspective view of the sack holding ring; Fig. 6 is a view in elevation of the station trough with a car shown in a position to deliver a sack therein; Fig. 7 is a top plan view of the structure shown in Fig. 6; Fig. 8 is a longitudinal sectional view through the gun forming part of this invention; Fig. 9 is an enlarged transverse sectional view through the gun taken along the line 9—9 of Fig. 8; Fig. 10 is a sectional view taken along the line 10—10 of Fig. 8.

In this mail catcher there is provided a delivering device for delivering the sack to

the train. In order to accomplish this there is provided a gun 11 which is secured to the supporting arm 12 of the standard 13 which standard is mounted upon the platform 14 positioned adjacent the track. Within the gun there is provided a plunger 15, the stem 16 of which extends through the head 17 of the gun and is provided with teeth 18, thus forming a rack which is engaged by the pinion 19. This pinion 19 is rigidly mounted upon the shaft 20 of the wheel 21, the shaft being rotatably mounted in the bearing brackets 22 so that by turning the wheel 21, the stem may be moved outwardly, thus drawing the plunger 15 to the position shown in Fig. 8 against the tension of the spring 23. In order to releasably hold the plunger in the set position there is provided a pawl 24 which is yieldably held in a normal position by the spring 25 and extends through an opening formed in the shoulder 26 into the gun, thus permitting its free end to enter the socket 27 of the plunger. A line 28 is connected with the upper end of the pawl 24 and after being passed around the pulleys 29 is connected with the bell crank lever 30 which forms the trigger. In order to move the trigger a finger 31 is secured to the car 32 in such a manner that its upturned outer end 33 will engage the free arm of the bell crank lever as the train passes the station, thus swinging the same to draw the line 28 and move the pawl 24 out of engagement with the plunger 15. As the plunger is released, the spring 23 will move the same toward the open end of the gun and the plunger will strike the mail bag which has previously been placed in the gun through the opening or doorway 34 which is closed by means of the cover 35. This sack will be driven out of the gun and will pass into the trough 36 of the chute 37, which communicates with the interior of the mail car. In order to prevent the plunger from moving toward the open end of the gun beyond a desired amount there has been provided an abutment lug 38 which will strike against the collar 39 of the head 17 and thus limit the movement of the plunger in one direction. It will thus be seen that the plunger will be automatically released as the train passes the station and that the mail bag will be driven out of the gun and into the chute through which it will pass into the interior of the mail car.

Adjacent the track there is provided a

trough 40 which extends parallel to the track and is supported by the standards 41. It should be noted that certain of these standards are shorter than the remaining ones, thereby causing the central portion of the trough to be curved downwardly as shown in Fig. 6. At one end of the trough there is secured a rod 42 which extends upwardly to engage the lever 43 of the catch 44 when the train passes the station. This catch 44 is pivotally connected with the arm 45 which extends from the mail car 32 and is so located that when in the position shown in Fig. 4 it may pass into the notch 46 of the block 47, carried by the sack holding ring 48.

When the mail car passes the station, the bag which is placed in the gun will be delivered to the car in the manner already described and the rod 42 will strike the lever 43, thus releasing the block 47 and permitting it to pass through the opening 49. The mail bag placed in the loop or ring 48 will then drop into the trough 40 and will slide along this trough, the downwardly inclined portion of the trough causing the sack to lose its momentum and thus come to a stop without violently striking the end of the trough. The bag can now be removed from the trough and a new one placed in the gun, the wheel 21 having been previously turned to draw the stem 16 outwardly until the pawl 24 enters the socket 27 to hold the plunger in a set position.

I have therefore provided an apparatus for delivering a mail bag to a station, the apparatus being so constructed that it will work automatically and therefore may be used for delivering and receiving mail bags from a train which is moving very rapidly.

It should also be noted that this apparatus is very simple in construction and therefore will not readily get out of order.

What is claimed is:—

1. In an apparatus of the character described, a receiving trough, a suspending arm provided with a cut out, a sack holding element, a block extending from said sack holding element through the cut out of said suspending arm and provided with a notch, a latch pivotally connected with said suspending arm and extending through the notch of said block to releasably hold the same in the cut out of said arm, a lever extending from said catch, and means ex-

tending from said trough to engage said lever and move the same to move said catch out of engagement with said block and permit a sack to drop into said trough.

2. In an apparatus of the character described, a track device comprising a trough and an actuating element extending above said trough, and a car device comprising a suspending arm, a sack holding element, and means movably connected with said suspending arm for engaging said sack holding element to releasably hold the same in engagement with said arm, said last mentioned means including a lever extending for engagement by the actuating element of said track device to cause the last mentioned means to be moved to a position to release said sack holding element.

3. In an apparatus of the character described, a train device including a supporting arm provided with an opening, a sack holding element including a block extending through the opening of said arm and provided with a cut out forming a seat, a catch pivotally connected with said supporting arm and extending into said seat to releasably hold said block in engagement with said arm, and a lever extending from said catch to permit said catch to be moved to an inoperative position.

4. In an apparatus of the character described, a receiving trough, a support, a gun carried by said support, a plunger slideable in said gun, resilient means for holding said plunger in a normal position, means for moving said plunger to a set position, said gun provided with an opening intermediate its ends, door means for closing said opening, an enlargement on the under side of said gun, a collar on said enlargement, a bracket depending from said collar, a pawl slideable through said enlargement and said bracket and projecting into said gun, a collar on said pawl; resilient means engaging said last mentioned collar and said bracket for holding said pawl in a set position, and means carried by said pawl whereby the same may be operated, substantially as described.

In testimony whereof I affix my signature in presence of two witnesses.

CLAIBOURNE FREMONT JACKSON.
